FIG. 9.

UNITED STATES PATENT OFFICE.

JAMES SILAS O'KEIFF, OF ALTOONA, PENNSYLVANIA.

FORM FOR CONCRETE STRUCTURES.

1,100,488.

Specification of Letters Patent. Patented June 16, 1914.

Application filed June 23, 1913. Serial No. 775,223.

To all whom it may concern:

Be it known that I, JAMES S. O'KEIFF, a citizen of the United States, and a resident of Altoona, in the county of Blair and State 5 of Pennsylvania, have made certain new and useful Improvements in Forms for Concrete Structures, of which the following is a specification.

My invention relates to forms for concrete 10 structures, my more particular purpose being to produce plates of suitable shape to be built into a mold to be used for concrete walls, the plates having such form that they may be readily connected together in different ways and also readily disengaged.

My invention further relates to an improved form of tie to be built into the wall, said tie being provided with means for facilitating the connection of the plates with 20 each other, and for bracing the wall molds as a whole until the concrete is set.

My invention further comprehends various details of construction suitable for use in connection with forms of this general 25 type.

Reference is made to the accompanying drawings forming a part of this specification, and in which like letters indicate like parts.

Figure 1 is a plan view of the composite wall mold for a building. Fig. 2 is a detail showing, in perspective, certain corner plates used in forming one of the outer corners of the mold. Fig. 3 is a section on the line 3—3 35 of Fig. 2, looking in the direction of the arrow, and showing one of the keys employed for holding the plates together. Fig. 4 is a detail showing in perspective two of the mold plates connected together by wall 40 ties. Fig. 5 is a vertical section through the parts shown in Fig. 4. Fig. 6 is a vertical section showing a form of my invention suitable for use in veneering wooden walls with concrete. Fig. 7 is a detail showing one of 45 the plates of special construction. Fig. 8 is a perspective showing a wall tie of a kind especially suitable for use in veneering. Fig. 9 is a perspective of another wall tie. Fig. 10 is a perspective of another tie, more 50 especially suitable for veneering work.

I provide a number of plates 9, each having a thick rim or border 10 integral with it. This rim is provided with lugs 11, also integral with it, each lug being provided with 55 a key slot 12 extending through it. The lugs of each plate are arranged in pairs the

lugs of each pair being in registry with each other so that the key slots 12 are in axial alinement, as may be understood from Fig. 4. Each plate 9 is further provided with 60 four notches 13, and with four lugs 14, partially bounding these notches and extending laterally away from the plane of the plate. Each of these lugs 14 is provided with a key slot 15. I also provide a few plates of the type shown at 9^a. These plates are for the most part like the plate 9, but they differ therefrom in being provided with slots 16, and with raised portions 17 encircling these slots for the purpose of strengthening the 70 plates 9^a immediately adjacent to the slots.

I provide a number of keys 20, each having a stem 18 and a tine 19, these parts being so arranged that the stem 18 may be extended through slots 12, 15, and the key may be turned by hand so as to lock two plates together. I also provide a number of wall ties 21, each having the form of a thin flat bar which may be made of cast iron or cast steel, or any other suitable material having strength combined with a certain amount of brittleness. Each wall tie 21 is also provided upon its oppositely disposed edges with notches 22 whereby it is weakened. Each wall tie 21 is further provided with key slots 22^a through 85 which the stem 18 of a key may be extended. Two portions 23 of each wall tie 21 carrying the key slots 22^a are adapted to be broken off from the main body portion of the tie. This is why the notches 22 are provided. For the 90 purpose of rendering the mold as a whole adjustable within certain limits as to size, I provide some plates 24 of different width in one direction than in another, as may be understood from Fig. 7. These plates 24 are 95 provided with lugs 25 corresponding to the lugs 11 of the plates 9. I also provide corner plates 26 having lugs 27, these corner plates being especially adapted for shaping the angles of the inner facing or wall of the 100 mold, as may be understood from Fig. 1. A portion of the concrete in a plastic condition is shown at 28.

The form of the plates 24 may be understood from Fig. 7. Each of these plates is 105 provided with two lugs 29 extending laterally from it, and with two notches 30 which are partially bounded by these lugs. Each plate 24 is further provided with a slot 31 and with a thickened portion 32 encircling 110 this slot. This plate with its slots 31 may be used after the manner of the plate 9^a pro-

vided with its slots 16, as above described—the only difference being that the plate 42 is narrower than the plate 9^a.

In Fig. 6 I show how my invention may be employed for the purpose of attaching veneering to wooden walls already constructed. The weather boarding, or outer facing of the wall is shown at 34, the inner facing appearing at 33, and between these facings is a spacing timber 35. At the bottom of the outer face 34 is a beam 36. In order to apply veneering of concrete to such walls I use the bracket shown in Fig. 8. This bracket is provided with a base 37 and with a tie bar 38 integral with this base. The tie bar 38 is provided with a key slot 39 and with notches 40 for the purpose of weakening the tie bar and thus enabling it to be readily broken at the proper time. The bracket 37 is provided with notches 41, 42. By driving nails or screws 43 through these notches, the base 37 of the bracket is secured upon the adjacent wall facing 34. This being done, a plate 9 may be connected with the outer end of the wall tie 38 by aid of keys 18. Any number of the plates 9 may thus be connected edge to edge, as well as to wall ties 38. By placing other plates 9 upon the top of the plate 9 shown in Fig. 6, and securing the lower edge of one plate to the upper edge of the plate below it, by aid of the keys 20, the mold may be constructed of any desired height. Concrete 44^a being poured into the mold and allowed to set, the plates 9 may be removed. The wall ties 38 together with their bases 37, however, are embedded in the concrete and there remain. After the concrete has set the outer or projecting ends of the plate 9 are removed. The outer or projecting portions of the wall ties may be broken off at the notches 40. Each tie 38 is provided with a pin 43^a which becomes embedded in the concrete and serves to prevent the same from working loose from the tie and consequently from the wall. In some instances, I form the tie, when used for veneering, as shown in Fig. 10. A plate 44 is provided with a hole 45 to accommodate a nail, screw, or other fastening, and is further provided with a projecting flat portion or bar 46, the edges of which are provided with corrugations 47. This construction facilitates holding the concrete rigidly in position.

The projecting end portions of the ties shown in Figs. 8 and 9 may be used to facilitate the building and removal of scaffolding. The scaffolding is built upward from the ground and rested at its different stages or landings upon the extending portions of the wall ties. After the completion of the work, however, the scaffolding is removed, beginning at the top, and as it is

taken down, projecting portions of the wall ties are broken off, beginning at the top of 65 the wall.

The operation of my device is as follows: The plates 9, 9^a, and 26 are connected together as above described and as shown, say, in Figs. 1, 4 and 5, so as to form a wall 70 mold. Concrete 28 is next poured in between the inner and outer facings of the mold and is allowed to set. The plates are next disengaged from each other and moved higher up and again connected with each 75 other and with the wall. More concrete being added, the wall is built up higher than it was at first. A comparatively few plates in active use may thus be employed for constructing a wall of practically any desired 80 height. When the wall is completed the portions 23 of the wall ties 21 are broken off. This may thus be done as the scaffolding is taken down, beginning at its top. By the time the last of the scaffolding is removed all of the wall ties will be broken off. The middle portion of each wall tie 21 remains permanently in the wall.

In applying veneering of concrete as above described with reference to Fig. 6, a 90 portion of each tie 38 and all of the accompanying bases 37 remain permanently embedded in the veneering.

I do not limit myself to the precise construction shown, as variations may be made 95 therein without departing from the spirit of my invention.

I claim:

A wall mold of the character described comprising spaced series of mold plates or 100 panels having smooth inner faces, each of said plates or panels being substantially rectangular in form and having its vertical side edges provided with outwardly projecting lugs the outer faces of which are 105 flush with said edges and each of which plates or panels is provided along its upper and lower horizontal edges with notches and with outwardly projecting lugs the outer surfaces of which are flush with the 110 bases of the notches, the said lugs of said mold plates or panels having key slots, wall ties extending between the upper and lower edges of the mold plates or panels and having their end portions extended into the 115 notches and provided with key slots, keys for connecting the ends of the wall ties and the adjacent lugs of the wall plates or panels, and keys for connecting the side lugs of adjacent plates or panels in a horizontal line.

JAMES SILAS O'KEIFF.
